UNITED STATES PATENT OFFICE.

JACOB L. SCHMEHL AND EDWARD M. MACNALLY, OF SOUTH BETHLEHEM,
PENNSYLVANIA.

ROTARY ENGINE.

1,034,519.

Specification of Letters Patent. Patented Aug. 6, 1912.

Application filed October 9, 1911. Serial No. 653,599.

To all whom it may concern:

Be it known that we, JACOB L. SCHMEHL and EDWARD M. MACNALLY, citizens of the United States, residing at South Bethlehem, 5 in the county of Northampton and State of Pennsylvania, have invented certain new and useful Improvements in Rotary Gas-Engines, of which the following is a specification, reference being had to the accompanying drawings.

Our invention relates to new and useful improvements in internal combustion engines and more particularly to a rotary gas engine, and our object is to provide a device 15 of this character wherein the volume of the compartments which receive gases is decreased up to the ignition point and increased after ignition as the rotor revolves.

A further object of the invention resides 20 in the provision of a rotor, the blades of which are so constructed as to be capable of compression or contraction laterally.

Still another object of the invention resides in the provision of a cylinder, the heads 25 of which have the inner faces thereof formed as cams, whereby the contraction and expansion of said blades will be effected.

A still further object of the invention resides in forming the blades of the rotor of 30 sections, which sections are acted upon by springs normally tending to force the same outwardly and into engagement with the inner faces of the cylinder heads.

A still further object resides in the provision of a device which is extremely simple 35 and durable in construction, and one which is very effective and useful in operation.

With these and other objects in view, our invention consists in the novel features of 40 construction, combination and arrangement of parts as will be hereinafter referred to and more particularly pointed out in the specification and claims.

In the accompanying drawings forming a 45 part of this application, Figure 1 is a side elevation of the device partly in section.

Fig. 2 is a vertical transverse section therethrough as seen on line 2—2, Fig. 1. Fig. 3 is a transverse section through one of the 50 blades of the rotor as seen on line 3—3, Fig.

2. Fig. 4 is a vertical section through one of the blades as seen on line 4—4, Fig. 3, and, Fig. 5 is a vertical section through one 55 of the blades as seen on line 5—5, Fig. 3.

In carrying out our invention, we shall

refer to the drawings in which similar reference characters designate corresponding parts throughout the several views and in which—

1 indicates a base or sole plate upon which 60 is mounted or formed integral therewith vertically extending and spaced apart supports 2, which supports form bearings for a rotatable shaft 3 extending therethrough. Mounted on the sole or base 1 intermediate 65 of any two of the bearings 2, is a cylinder 4 which may be of any size desired, and secured to the cylinder at the ends thereof, are the heads 5 and 6, respectively, through which extends the shaft 3.

Mounted within the cylinder 4 is a rotor 70 which comprises a plurality of blades 7 radiating from the shaft 3, said blades being of a size adapted to constantly contact with the inner wall of the cylinder proper and 75 the inner faces of the cylinder heads 5 and 6. The provision of this plurality of blades 7 on the shaft, when mounted within the cylinder, as disclosed in Fig. 2, provides a plurality of compartments 8 within said cylinder, and it will be appreciated that when 80 the pressure is received within these compartments, the impact thereof against the blades 7 will tend to revolve the rotor within the cylinder to correspondingly rotate the 85 shaft 3. In order to provide means whereby the explosive mixture may enter within the compartments 8, we provide the cylinder 4 with an inlet port 9 in one side thereof below 90 its axis, which port communicates with a chamber or inlet valve cage 10 formed on the outer periphery of said cylinder. The chamber 10 is also provided with an inlet valve 12 which communicates through the 95 medium of a pipe 13 with any desired gas storage means (not shown), and any desired means may be provided for the operation of this valve so that the explosive mixture may enter within the chamber 10. After the 100 gases have entered the chambers 8 of the cylinder, the same are adapted to be compressed through a means which will be hereinafter and more particularly described, and then fired at the highest point of pressure by means of a spark plug or the like 11, so that 105 the expansion of the burned gases will tend to aid the rotation of said rotor.

As the rotor revolves within the cylinder through the explosion and the expansion of the gases within the compartments 8, the 110

burned gases within said chambers 8 will be exhausted through the exhaust ports 14 and 15 in the bottom of said cylinder 4, and in order to provide for the expansion and compression of the gases in the compartments 8, we provide an improved form of blade 7 which cooperates with the inner faces of the cylinder heads to increase and decrease the volume of the compartments between the respective blades in the space covered between the inlet and exhaust ports as the rotor is revolved within the cylinder. In order to effect this result, we first provide the heads 5 and 6 with inner cam faces 16, said cams being formed identically on both heads and the blades 7 are so constructed as to yield to the irregularities of the cams. These improved forms of blades comprise an outer channel-shaped blade member 17, the inner or base portion of which is mounted on the shaft 3, said member 17 being of a width substantially equal to the distance between the innermost points of the cam 16 on the heads 5 and 6. Mounted in the channel-shaped member 17 so as to project beyond each side edge thereof, are the telescoping channel-shaped members or slides 18 and, as shown in the drawings, we have provided four of these members 18 with a pair for each side edge, but it will be understood that as many may be telescoped within one another, as desired. Mounted within each of the telescoping slides 18, is a flat slide member 19, and loosely extending through all of said slides, are the upper and lower guide bars 20 and 21. These guide bars retain the slides in proper position within one another and within the outer member 17, and in order to retain said slides normally in their extended positions, as shown in Fig. 3, a plurality of coil springs 22 is provided and encircled about said guide bars 20 and 21, a coil spring being provided between each pair of slides, thereby forcing the one outwardly from the other. When properly positioned within the cylinder, it will be seen that the tendency of these springs 22 will be to force the slides or sections of the blade, as they may be termed, laterally so that the outer slide members 19 will engage or contact with the inner faces of the heads 5 and 6 of said cylinder, and during the rotation of the rotor within the cylinder, the cam surfaces on the inner faces of the cylinder heads will be compensated for by the yielding of said slides through said springs 22.

The cam surfaces on the inner cylinder heads are so arranged that when the explosive mixture passes from the chamber 10 through the port 9 and into the compartments 8, the blades are expanding to their greatest extent, allowing the greatest volume within the chambers 8, and as soon as said blades have passed the port 9 so that

the supply of gas for that particular compartment has been shut off, said blades will tend to compress through the medium of the cam faces 16. The contraction of the blades will decrease the volume of the compartments 8, thereby compressing the gases therewithin, and when the pressure of the explosive mixture within said chambers reaches its highest point, said gases are exploded by means of the spark plug 11. The tendency of the exploded gases to expand, will, of course, rotate the rotor and the expansion will be compensated for through the expanding of the blades, due to the arrangement of the cam faces 16, and after a certain amount of expansion has taken place, the blades are again contracted, through the cam faces, to force said exploded gases outwardly through the exhaust ports 14 and 15. Thus, it will be seen that the gases will enter the chambers when the volume of the latter is increasing, and as the rotor revolves, the volume will gradually decrease until the same is at the point of ignition, whereupon the blades again tend to gradually expand, making room for the expansion of the exploded gases as the rotor revolves, and the blades are then compressed for a second time during the revolution of the rotor to force the exploded gases outwardly through the exhaust ports.

In order to provide means whereby the compression within the chambers 8 will not be lost, the outer or free edges of the outer member 17, and the upper and lower edges of the slides 19 are provided with additional strips 23, and the outer edges of said member 17 and the upper and lower edges of the slides 19 are provided with sockets or the like 24 which receive therein small coil springs 25, said coil springs being adapted to contact with the inner faces of the strips 23 to force the same outwardly and into engagement with the contacting surfaces of the objects which they may meet. The strips on the outer edges of the member 17 and the strips on the upper edges of the slides 19 are adapted to contact with the inner wall of the cylinder 4, while the strips on the lower edges of the slides 19 are adapted to contact with the shaft 3, and thus, all possible chance of the loss of any compression within the chamber 8 will be prevented and chance for back firing eliminated.

From the foregoing, it will be seen that we have provided an improved form of rotary gas engine wherein means has been provided for the increasing and decreasing of the volume of the compartments between the blades of the rotor. It will further be seen that this means is accomplished by providing cam surfaces on the inner faces of the cylinder heads and providing spring or compression blades on the rotor, which blades are adapted to yield to the irregularities

ties of the cam surfaces. It will further be seen that by arranging the cams so that the spring blades will be opening at the inlet port and so that said blades will be compressed at the exhaust ports, gases which will enter, will be compressed, ignited and exhausted as the rotor revolves, thereby aiding manifestly in the operation of the device. It will still further be seen that our device is comparatively simple in construction, thereby readily and cheaply manufactured, one which is very durable in construction, and one which is effective and useful in operation.

15. What we claim is:—

1. An engine of the class described, comprising a cylinder provided with inlet and exhaust ports, a rotor within the cylinder having a plurality of radial blades thereon; 20 said blades being formed of a plurality of telescoping sections, means to normally force the inner sections of the blades outwardly and laterally, and means to cause the contraction of said sections as the rotor 25 revolves.

2. An engine of the class described, comprising a cylinder provided with inlet and exhaust ports, a rotor within the cylinder having a plurality of radial blades thereon, 30 said blades being formed of a plurality of telescoping sections, spring means to force certain of the sections outwardly and laterally, and means on the cylinder heads to cause the contraction of said sections as the 35 rotor revolves.

3. An engine of the class described, comprising a cylinder provided with inlet and exhaust ports, a rotor within the cylinder having a plurality of radial blades thereon, 40 said blades being formed of a plurality of telescoping sections, spring means to force certain of the sections outwardly and laterally, and cam surfaces on the inner faces of the cylinder heads with which the outer sections of the blades are adapted to contact.

4. An engine of the class described comprising a cylinder provided with inlet and exhaust ports, a rotor within the cylinder having a plurality of radial blades thereon, 50 said blades being composed of outer chan-

nel-shaped members, inner slide members telescoped therewithin and capable of lateral movement with respect thereto, guide means for said inner slide members, means to normally force said slide members outwardly and laterally, and means to cause the contraction of said sections as the rotor revolves within the cylinder.

5. An engine of the class described comprising a cylinder provided with inlet and exhaust ports, a rotor mounted therewithin and provided with a plurality of radial blades, said blades being composed of outer channel-shaped members, additional channel-shaped members telescoped within said outer members, inner flat slide members telescoped within said additional channel-shaped members, guiding means for said telescoped channel and flat slide members, spring means to normally force the same outwardly and laterally with respect to said outer channel-shaped members, and means on the cylinder heads to cause the contraction of said movable member as the rotor revolves.

6. An engine of the class described comprising a cylinder provided with inlet and exhaust pipes, a rotor mounted therewithin and provided with a plurality of radial blades, said blades comprising channel-shaped outer sections, additional channel-shaped slide sections telescoped therewithin, flat central slides telescoped within the additional channel-shaped members, guide rods loosely extending through said slide members, and spring means encircling said guide rods between the respective slide members to normally force the same outwardly and laterally with respect to the outer channel-shaped members, and means on the cylinder heads to cause the contraction of said slide members as the rotor revolves.

In testimony whereof we hereunto affix our signatures in the presence of two witnesses.
